UNITED STATES PATENT OFFICE.

GEORGE W. HUDSON, OF LANCASTER, OHIO.

COMBINED TABLE AND IRONING-BOARD.

1,391,115.

Specification of Letters Patent. Patented Sept. 20, 1921.

Application filed February 25, 1920. Serial No. 361,246.

To all whom it may concern:

Be it known that I, GEORGE W. HUDSON, citizen of the United States, residing at Lancaster, in the county of Fairfield and 5 State of Ohio, have invented certain new and useful Improvements in Combined Tables and Ironing-Boards, of which the following is a specification.

This invention relates to a combined ironing board and table and has as one of its 10 principal objects to provide a construction wherein the ironing board will normally be disposed beneath the table top in a position out of the way but wherein, when desired, 15 the ironing board may easily be swung to active position supported on top of the table.

The invention has as a further object to provide a construction wherein the table will include a swingingly mounted section 20 and wherein the ironing board will be fixed to the lower side of said section so that when the section is in its normal position, the ironing board will be supported thereby beneath the top of the table while, when 25 the section is swung to rest upon the fixed section of the table top, the ironing board will be disposed in active position.

And the invention has as a still further 30 object to provide a construction wherein the table will be equipped with an apron designed to prevent the clothes, as they are ironed, from dragging on the floor.

Other and incidental objects will appear hereinafter.

35 In the drawings:

Figure 1 is a perspective view of the combined ironing board and table.

Fig. 2 is a perspective view showing the ironing board swung to active position.

40 Fig. 3 is a transverse sectional view taken through the structure when the ironing board is swung upwardly, and

Fig. 4 is a transverse section taken through the structure when the ironing 45 board is in inactive position.

In carrying the invention into effect, I employ a table which includes a frame having parallel side bars 10 and 11 respectively, joined by parallel end bars 12. Extending from the frame at its corners are the legs 13 of the table and slidably through the front side bar 10 is a drawer 14.

Secured upon the forward portion of the table frame is a fixed top section 15 and 50 mating with this section to normally extend in alinement therewith is a movable top sec-

tion 16 secured to the fixed section by suitable hinges. As will be observed, the section 16 is somewhat wider than the section 15. Mounted upon the lower side of the movable top section to extend longitudinally thereof is an ironing board 17. This ironing board is supported adjacent one end by spaced blocks 18 and engaging through the board and through said blocks are screw 55 bolts or other approved fastening devices 19 firmly connecting the board with the top section 16. As is usual, the board is preferably tapered toward its outer end and hinged beneath the outer end of the board is a leg 60 20 coacting with the top section for sustaining the outer end portion of the board.

As will now be readily appreciated, when the section 16 is swung to closed position resting upon the table frame in alinement 75 with the section 15, the two sections will, as shown in Fig. 1, coact to form the table top so that when it is not desired to employ the ironing board, the table may be used as an ordinary table. However, when it is 80 desired to use the ironing board, it is simply necessary to swing the section 16 of the table top to open position lying upon the section 15 when the ironing board will be supported on top of the table in conveniently 85 accessible position. In this connection, it is to be observed that when the movable top section is closed the ironing board is, as particularly shown in Fig. 4, disposed within the table frame and lies within the lines 90 thereof. The ironing board will thus be protected by the table frame so that objects cannot easily strike the board while the presence of the ironing board upon the table will not be readily discernible. Further, it 95 will be noted that the section 15 forms the front section of the table top while the section 16 forms the rear section. Consequently, when the section 16 is closed, the ironing board is disposed adjacent the rear 100 side of the table while when said section is open the ironing board is disposed adjacent the forward side of the table so that the board may be easily reached.

When the section 16 of the table top is 105 swung forwardly, an opening is, of course, created through the table frame and closing said opening is an apron 21. At its forward margin this apron is secured beneath the rear margin of the section 15 of the top 110 while at its rear margin, the apron is secured to the upper edge of the side bar 11 of

the table frame. The end margins of the apron are secured to the upper edges of the end bars 12 of the table. Thus, when the top section 16 is open and clothes are being 5 ironed upon the ironing board, the apron will prevent the clothes, as they are moved rearwardly across the board, from dragging on the floor. On the other hand, when the top section 16 is closed, the apron will 10 operate with said section to form a housing for the ironing board for excluding dust or dirt therefrom. I accordingly provide a particularly effective construction for the purpose set forth and a combined ironing 15 board and table which is particularly simple in its structural details. Mounted upon the top section 16 adjacent the larger end of the ironing board is an iron stand 22 upon which an iron may be conveniently rested 20 when not being used.

Having thus described the invention, what is claimed as new is:

A device of the character described including a table frame, a fixed top section secured thereon and covering a portion of the 25 frame, a movable top section hinged to the fixed top section, the two sections when aligned horizontally covering the entire top of the table frame, an ironing board fixed to one side of the movable section and 30 housed within the table frame when the two sections are horizontally aligned, and an apron extending between the fixed top section and the side and ends of the frame to house the ironing board when it is not in 35 use and to support ironed articles in rear of the ironing board when the latter is in use.

In testimony whereof I affix my signature,
GEORGE W. HUDSON. [L. S.]
